OIL PURIFYING DEVICE

James E. Hurn, La Porte, Ind., assignor to De
Luxe Products Corporation, a corporation of
Indiana

Application March 16, 1936, Serial No. 69,217

21 Claims. (Cl. 210—131)

This invention is a method of and mechanism for clarifying and filtering lubricating oil, and more particularly for freeing lubricating oil in an internal combustion engine from impurities.

5 This invention is a continuation-in-part of my co-pending application, Serial No. 702,529, filed December 15, 1933.

Oil filters heretofore produced for internal combustion engines have attempted to procure 10 filtering primarily by the use of straining means which will in time build up a layer of impurities sufficient to procure better filtering. The present invention is directed toward the use of a thick body of absorbent filtering medium through 15 which oil is seeped under low velocity. In this manner, it is possible to divert only a small portion of the oil employed in an internal combustion engine and filter it so thoroughly that visual cleanliness as well as the necessary chemical 20 cleanliness is maintained in the whole body. Experience has shown that with a filter of the type herein described, oil may be used without change during fifty thousand miles or more of driving.

25 The invention is illustrated in the drawings, in which—

Fig. 1 is a sectional elevation of a filter designed for use on an ordinary passenger automobile, the filter being drawn to scale; Fig. 2 is a sectional elevation of the helical spring supporting means within the cartridge of the filter; Fig. 3 is a detailed sectional view of the valve; Fig. 4 is a sectional elevation illustrating a dual filtering system; Fig. 5 is a sectional plan of an 30 apparatus for forming a cartridge and having thereon a cartridge partially formed; Fig. 6 is an elevation of a metallic cartridge cover; and Fig. 7 is a view of a cartridge.

As illustrated in the drawings, 1 represents a 35 filter housing, 2 is a cover enclosing the top thereof, and 4 represents a sump portion which is provided with a shoulder 3 adapted to support a cartridge. A tubular member 5 is fixedly seated in the bottom of the sump 4 and extends upwardly and centrally through the filter. The upper end of the tube is preferably threaded and a threaded extension 10 fitted therein. At the base of the filter an oil inlet 6 is provided which is tapped on to the pressure line leading from 40 the internal combustion engine in such manner as to produce parallel flow through the filter. The diameter of the inlet 6 for an ordinary combustion engine is $\frac{1}{8}$ " internal diameter, taking off from a pressure line which is usually at least 45 $\frac{3}{8}$ ". The inlet line is markedly narrowed at the

passage 7, this passageway having an internal diameter of $\frac{1}{8}$ " on a truck size filter and $\frac{5}{64}$ " on a passenger car filter. The passageway 8 and the tubular member 5 are $\frac{3}{8}$ " in diameter. In an upper portion of the tube, two openings 9 are provided $\frac{1}{8}$ " in diameter, through which oil is passed in a rapidly moving thin stream against the cone 11. This cone is made preferably of a rigid material, for example, thin sheet metal, say of 30 gauge, and preferably is integrally connected to the filtering cartridge. Its upper portion is unbroken and its lower portion is provided with a large number of small perforations 12 through which oil passes into the filtering medium 13. The base 14 of the cone is seated upon the shoulder 3 of the sump 4.

Within the cartridge are provided means for supporting the normal resistance of the filtering medium to compression, which properly is in the form of a helical spring 15 which is affixed to the base 14 by welding or preferably by insertion of an end 16 of the spring in a groove 17 in the base. The filtering medium preferably consists of cellulose fibers, which have the property of reacting with any sulfuric acid formed in the engine and thereby removing the same. The fibers should be extremely long and interconnected to prevent any possibility of channeling and should be dense enough to prevent compression, but not too dense to prevent free seepage of oil therethrough. The preferred method of forming a cartridge will be set forth hereinafter.

A sack or bag 18 is attached to the top 19 of the cone 11 and surrounds the filtering medium, its other end 20 being fastened over the base of the 30 cone, for example, by a shirr string.

The cartridge 20, so formed, fits about the tubular member 5 and within the housing 1. It is surmounted at the top by the perforated cap 22, shown in detail in Fig. 6. The nut 23 is threaded 40 on the extension 10, thus securing the cap 22 to it as a unit, and permitting removal of the cover at the same time as the extension 10 is removed. The extension 10 is pierced by the narrow passageway 24. The size of this passageway is correlated to the oil filtering capacity of the cartridge and the size of the inlet 7 so that when the ball valve 25 is open the capacity of the filter will be substantially the same as the amount of oil admitted at the bottom, and thus will not build up 45 pressure or substantially reduce it. The size of the passageway will depend upon the characteristics of the cartridge and also upon the characteristics of the oil employed. For most purposes, a diameter of $\frac{1}{16}$ " is desired. This extension is 50

55

shown in detail in Fig. 3. The ball valve 25 closes on the seat 26, which should be smooth and cut back sharply enough to provide full flow for opening of the valve. The valve is held normally in closed position by the spring 27 which may be adjusted by the screw 28. A plug 29 is provided above the seat screw fitting against the shoulder 30 in the wheel 31. The upper portion of the extension 10 forms an enlarged knob 32 which is transversely pierced by the handle 33.

The cover 2 is seated about the extension 10 below the knob and the washer 34 and likewise may be integrally removed with the cap 22. A gasket 35 is provided between the cover 2 and the shoulder 36 of the housing. A chamber 37 is formed between the cap 22 of the cartridge and the cover 2 of the housing and from this the outlet 38 is connected in any suitable manner to the crankcase. The opening 38 is large enough to remove all oil filtered through or passed through the valve 25 without building any substantial pressure in the chamber 37. Normally, a $2\frac{1}{4}$ " opening is sufficient.

A drain 39, fitted with a plug 40, is provided at the base of the sump.

The formation of the cartridge is of great importance in the production of a successful filter. The material of the cartridge should be such that strong acid such as sulfuric, which may be formed in an internal combustion engine, will be chemically removed by the filtering material. Cellulosic fibers, such as cotton, paper and the like, will remove such acids, when formed, by reacting therewith. The material and its method of agglomeration must likewise be such as to prevent any substantial channeling of oil through the filter upon use. Channeling is extremely difficult to prevent, and any loose heterogeneous mass of material will channel badly unless special precautions are taken to prevent it. The cartridge should also be of such a density that it will permit oil to flow through it freely and yet remove from it the impurities, and likewise must have sufficient elasticity or rigidity that it will not compress markedly under the permitted stresses to which it is subjected. In the present filter, this requires a correlation between the pressure at which the valve 25 will open and the compression point of the cartridge. For example, a cartridge is hereinafter produced to withstand a pressure of the order of 40 pounds per square inch without noticeable compression, and accordingly the valve 25 is set so that the cartridge will not be subjected to any greater pressure drop across the cartridge. At the same time, in the present structure it is considered that the back pressure from the chamber 31 will be zero under the conditions where the operating pressure on the valve 25 exceeds 40 pounds and therefore the maximum pressure to which the cartridge is subjected, as well as the pressure drop across it, is limited to the compression point thereof.

In Fig. 5 is illustrated the preferred manner of producing the cartridge. The string material is pure cotton thread, free from lint and short ends and what in the trade is known as thread stock in knotted form, which consists of broken bobbins of various size threads. This material is known as No. 659 white yarn waste and preferably has a minimum thread size of 70, and a maximum not over 40. These threads form loose yarns containing about 10 to 200 threads in each strand. The strands having much more thread than this are discarded (generally those which have a diameter of more than $1\frac{1}{4}$ " when loose). These

strands are passed through rollers to crush the knots, and then are ginned upon a large rotating wheel having rows of teeth 4 to 5 inches apart and about an inch apart in the rows. The wheel has a diameter of about 40" and a width of about 12". It rotates at about 40 R. P. M. and the thread winds up upon it. The mass is then removed in the form of a band of loose yarn material, the broken groups or masses of threads being stretched out but not losing their identity. The loose or short ends are discarded, and the material is then weighed out in the desired amounts. A seven-foot section of this material contains about enough material for one cartridge. The requisite amount of material for a cartridge is measured, the rope of material is then divided about in half to form a fourteen-foot rope of half the size, and is fed into the winding device shown in Fig. 5.

This device comprises a spindle 41 carrying a chuck 42, provided with two pins 43 which engage corresponding perforations 44 in the base of the cone 45, which has been fitted over the spindle from the other end. A cylinder 47 encloses the spindle. The spring 48, which is a lefthand wound helical, has previously been attached to the base of the cone, and its last convolution forms a triangular slot adjacent the base. A cover plate 49 is supplied at the opposite end of the spindle and is held in place by the block 50. In many instances, a small amount of the thread material is wrapped about the base of the cone and under the spring, there sometimes being difficulty in securing complete and uniform stuffing at this point. The spindle is then rotated at about 60 R. P. M. in the direction such that the end of the cotton will be caught under the spring and held there. The cotton is spread in a ribbon approximately the length of the cartridge and is fed through a slot 51 of about $\frac{3}{8}$ " diameter while held by the workman under considerable tension. The material is fed to produce a uniform cartridge, the strands being moved forward, if necessary, as one portion of the cartridge becomes filled. The tension provided is sufficient that $7\frac{1}{2}$ ounces of the cotton fibers will occupy 62 cubic inches of cartridge space. If the material is wound too hard, it will expand after removal from the cylinder. The cartridge preferably should be able to stand, with the spring, a compression limit of 40 pounds, plus or minus 5 pounds.

When the material has been filled in, it will be in the form of circumferentially parallel or spirally wound fibers, tightly wound in and about the helical in such manner that channeling does not occur on use of the cartridge.

The bag 52 before the winding operation is attached to the top of the cone and lies flat along the spindle, a rubber band (not shown) holding it on the cone. At the close of the operation, the block 49 and plate 45 are removed and the stocking pulled over the outside of the cylinder 47. The cartridge is then pushed out of the cylinder by the chuck 42 into another friction member 53, which pulls the stocking 52 back and holds the cotton in, the stocking being stretched considerably and pulled down over the outside and fastened by a shirr string over the base of the cone.

The wire handle 54, shown in Fig. 7, is then inserted and passed underneath the upper loop of the helical, the open ends being spotwelded and drawn into the cartridge. Such a handle provides a positive non-corroding means of with-

drawing the cartridge from the filter and eliminates the use of tools for this purpose.

A cartridge satisfactory for use in ordinary passenger car engines is $5\frac{1}{4}$ " long by 4" in diameter, and contains 69.2 cubic inches, of which 7.2 cubic inches is occupied by the hollow cone. This type of cartridge contains $7\frac{1}{2}$ ounces of cotton material. For other larger motors the larger cartridge is used, for example, with a truck motor, a 6" high cartridge of the same diameter and containing 9 ounces of cotton, may be employed.

A preferred size of cone has a base of $3\frac{3}{4}$ ", an internal diameter of 2 inches at the bottom, and a height of 3.75". With such a cone, a large number of small holes is preferred. For example, it has been found that holes of $\frac{1}{8}$ " in diameter, separated approximately $\frac{3}{16}$ ", beginning about an eighth of an inch above the base of the cone, and arranged in circumferential rows of holes about 10 deep, are preferred. This will provide approximately 250 holes extending approximately two inches into the cone.

The orifices 9 preferably discharge oil into the cone at a point about halfway between the top holes and the top of the cone.

The angle of the cone is so correlated to the flow of oil and the size of the sump that a quiescent body is provided within which impurities may settle out of the oil. With the system shown, the oil moving from the orifices 9 impinges in a narrow moving stream upon the upper rigid walls of the cone in a manner to precipitate large impurities, but at the same time keep the walls of the cone clean. The oil then moves downwardly, its area of flow increasing, and its velocity therefore decreasing, but sufficient velocity being maintained along the edges of the cone so that the wash of oil across the openings 12 is sufficient to keep them from clogging with impurities, as is frequently the case where oil is discharged directly into a filtering medium. At the same time, at the lower portion of the cone and in the sump, a zone of quiescence is provided within which heavy impurities may settle out.

The helical 15, which is anchored, as described, on the base of the cone, is formed of heavy steel material $\frac{1}{8}$ " in diameter and of sufficient strength to withstand 40 pounds compression when combined with a mass of cotton material. This means generally that the spring will stand 10 pounds pressure at $3\frac{3}{4}$ " length without the cotton material.

The spring is $4\frac{1}{4}$ " high, has an external diameter at the bottom of $3\frac{3}{4}$ ", $2\frac{1}{2}$ " in the middle, and $5\frac{1}{8}$ " at the top. It is preferably shaped to follow the inclination of the cone, up to and including the first turn above the highest opening in the cone, and from that point on, the slope of the helical is reversed to provide maximum support to the upper mass of filtering medium.

It is important in preparing the filter to correlate the mass of filtering medium to the amount of oil passing therethrough; to correlate the viscosity of the oil to the depth of the mass, and also the depth of the mass to the area of it through which oil may enter. This means in many instances that doubling the inlet area for the oil means more than doubling the mass of filtering medium above it. For this reason, it has been found advisable in many instances to use a dual installation in which a pair of cartridges are fed in a single system rather than to attempt to build a larger unit, inasmuch as there may be a

considerable saving in the amount of material required.

It will be noted in the construction of filters shown that from the time the oil passes through the orifices 9 until it has completed its passage through the filter, its available area of flow is being constantly widened. Thus, after leaving the orifices the oil passes down the cone, the cross sectional area of which is constantly increasing, and thereafter enters the cartridge at its narrowest point and flows upwardly therethrough, likewise with increasing cross section. This permits better distribution of impurities throughout the cartridge, there being less of a tendency for all of them to be deposited at the beginning.

The shape of the cartridge also is such that impurities tending to settle out after long use do not clog the oil entrances, but in the event of such settling will be caught in the lower legs of the cartridge.

The construction of the filter is such that oil passing through it may be considered as being in several well defined pressure zones, which are induced by the various valve-like passages through which the oil is forced to proceed. For example, with a line pressure of 40 pounds, the pressure upon the valve 25 has been found to be 20 pounds (this test being with an S. A. E. 40 oil), the pressure in the sump 15 pounds, the pressure in the middle of the cartridge 13 pounds, and the pressure in the top of the filter housing 8 pounds. The pressure in the top is larger, due to the high viscosity of the oil, there being no substantial pressure in the top with a lighter or hotter oil. When the line pressure was reduced to 30 pounds with the same oil, the valve pressure became 15, the sump pressure 12, the cartridge pressure 10, and the return pressure $6\frac{1}{2}$.

The figures given below indicate the typical amount of oil passing through oil filters equipped in accordance with this invention and with cartridges prepared as herein described, under various conditions.

The term "base" as applied to the filter cartridge herein is used to denote the side thereof from which the oil enters, regardless of the position thereof with respect to the vertical.

The following table shows typical satisfactory filter dimensions for ordinary truck and passenger car use. All dimensions are in inches.

Oil feed line 6	3 $\frac{1}{4}$	3 $\frac{1}{4}$
Orifice to tube	3 $\frac{1}{4}$	3 $\frac{1}{4}$
Tube internal diameter	3 $\frac{1}{4}$	3 $\frac{1}{4}$
Tube length	8 $\frac{1}{4}$	6 $\frac{1}{4}$
Orifices 9 diameter	3 $\frac{1}{4}$	3 $\frac{1}{4}$
Distance—orifice to cone	3 $\frac{1}{4}$	3 $\frac{1}{4}$
Cartridge height	6	5 $\frac{1}{4}$
Cartridge volume	(77.8)	62
Cartridge diameter	4 $\frac{1}{4}$	4
Cone diameter base	4 $\frac{1}{4}$	4
Cone internal diameter at base	2	2
Cone height	3 $\frac{3}{4}$	3 $\frac{3}{4}$
Cone holes diameter	3 $\frac{1}{4}$	3 $\frac{1}{4}$
Cone holes number	250	250
Cone volume	7.2	7.2
Helical height	434-514	434
Valve 25 pressure	40	40
Sump depth	34-2 $\frac{1}{2}$	17
Oil outlet diameter	3 $\frac{1}{4}$	3 $\frac{1}{4}$
Outlet 24 diameter	3 $\frac{1}{4}$ - $\frac{1}{2}$	3 $\frac{1}{4}$ - $\frac{1}{2}$
Cartridge material weight	9 oz.	7 $\frac{1}{2}$ oz.

A cartridge prepared in accordance with the foregoing disclosure has the unusual and inherent property of not substantially increasing its resistance to the passage of oil upon continued use, even to the point where the filter has absorbed within it all of the asphaltic material which it will retain. When this condition occurs the filter continues to pass oil but the oil which passes through it is not clean.

The foregoing detailed description has been given for clearness of understanding only, and no unnecessary limitations should be understood therefrom, but the appended claims should be construed as broadly as permissible in view of the prior art.

I claim:

1. A cartridge for a lubricating oil filter comprising a thick mass of fibrous absorbent material pierced at its base by a hollow conical depression and internally supported by a metallic helix, the convolutions of the helix being roughly parallel to the conical member throughout its extent.

2. A cartridge for an oil filter comprising a

- dense homogeneous fibrous mass packed tightly enough to provide no free channels for oil and to remove substantially completely in passage therethrough asphaltic oxidized materials formed in heated oil, and reinforced by an internal metallic support within the body of the absorbent material to provide throughout a highly compression resistant body.
3. A cartridge for an oil filter as set forth in claim 2 in which the support is a steel helix centrally located in the material.
4. A disposable oil filter cartridge having yielding sides adapted to form an oil seal with a housing within which the cartridge is fitted, a metallic base, a mass of absorbent material upon the base, an oil corrodable fabric casing enclosing the absorbent material, and a thin metallic bail at the top of the cartridge anchored to the metallic base.
5. A cartridge for a lubricating oil filter comprising a thick body of fibrous absorptive material packed tightly enough to remove asphaltic oxidized portions formed in the oil on heating, the base of said body being cut away to form a conic section, a rigid walled member of substantially impervious material within and contacting said section provided with a plurality of openings to the absorptive material at a lower portion of the section.
6. The method of filtering oil containing sludge which comprises passing the oil into a mass of absorbent material packed closely enough to prevent the entrance of gross particles of sludge, the movement of the unfiltered oil toward the absorbent material being in a direction and at a velocity to wash from the entrance face of the absorbent material substantially all sludge, whereby the face is continually kept free of sludge, and collecting sludge washed therefrom in a lower quiescent zone.
7. A cartridge for an oil filter comprising a dense homogeneous fibrous mass packed tightly enough to provide no free channels for oil and to remove substantially completely in passage therethrough asphaltic oxidized materials formed in heated oil, and reinforced by an internal supporting element within the body of the absorbent material to provide throughout a highly compression resistant body.
8. A cartridge for an oil filter comprising a dense homogeneous body of fibrous absorbent material packed tightly enough to provide no free channels for oil and to remove substantially completely in passage therethrough asphaltic oxidized materials formed in heated oil, said body having a density markedly less than the density of the absorbent material in it, said body reinforced by a supporting element separate from the body of absorbent material for supporting said body of absorbent material throughout its entire extent against compression under normal oil system pressures.
9. In an oil pressure system, an absorption type oil filter cartridge comprising, a dense homogeneous body of fibrous absorbent material packed tightly enough to provide no free channels for oil and to remove substantially completely in passage therethrough asphaltic oxidized materials formed in heated oil, said body having a density markedly less than the density of the absorbent material in it, said body reinforced by a supporting element separate from the body of absorbent material for supporting said body of absorbent material throughout its entire extent against compression under normal oil system pressures.
- pressures, means for supplying oil to the cartridge, means for removing filtered oil therefrom, and means for limiting the oil pressure on the cartridge to the normal pressure of the oil system.
10. An oil filter, comprising a housing enclosing a chamber having a sump in a lower portion thereof, a discharge opening for the sump, an oil filtering unit spacedly mounted in the housing above the sump, an outlet; a tube positioned in the housing chamber, its bottom opening providing an inlet for oil, and its upper end being provided with a valve assembly adapted to determine the maximum pressure of liquid in said tube, an outlet in the wall of said tube within the confines of the filtering unit, and a removable cover for said filter.
11. An oil purifying and filtering device having an inlet opening from the pressure side of a lubricating system and an outlet opening to the system, comprising a casing having a sump, an open top, an enclosing cover for said top, an elongated tube fixedly seated in the base of the casing including the inlet opening and extending upwardly through the center of the device to a point substantially in the plane of the rim of the open top, there being perforations in the wall of the tube within a filtering unit and a threading in its upper end, the cover being provided with a member central thereof having a threaded portion and adapted to coact with the threaded end of the elongated central tube and lock the device into a closed unit, and a filtering unit encircling the elongated tube above the settling chamber.
12. An oil filter comprising a housing enclosing a primary chamber, a thick resilient filter cartridge within the housing closing the primary chamber intermediately of its height, a metallic tube extending centrally through the chamber and the cartridge and provided with an opening to the cartridge and having an opening adapted to be connected to an oil lubricating system external to the filter, means for pressing the cartridge upon the tube to form a seal, a removable cover for the housing, and a locking means centrally assembled in the cover adapted to interlock with the upper end of the tube and assemble the housing, tube and cover into a unit.
13. An oil filter comprising a housing enclosing a primary chamber, a thick resilient filter cartridge within the housing closing the primary chamber intermediately of its height, a metallic tube extending centrally through the chamber and the cartridge and provided with an opening thereto between the ends of the cartridge and having an opening adapted to be connected to an oil lubricating system external to the filter, a removable cover for the housing, and a locking means centrally assembled in the cover adapted to interlock with the upper end of the tube and assemble the housing, tube and cover into a unit.
14. An oil filter comprising a housing enclosing a primary chamber, a thick resilient filter cartridge within the housing closing the primary chamber intermediately of its height, a metallic tube extending centrally through the chamber and the cartridge and provided with an opening thereto and having an opening adapted to be connected to an oil lubricating system external to the filter, a removable cover for the housing, a foraminous cap inside the cover, means associated with the cover for pressing the cap upon the cartridge to cause the cartridge to press itself upon the tube, and a locking means centrally assembled in the cover adapted to interlock with

- the upper end of the tube and assemble the housing, tube and cover into a unit.
15. An oil filter comprising a housing enclosing a primary chamber, a thick resilient filter cartridge within the housing, a metallic tube extending centrally through the chamber and at least partially through the cartridge and provided with an opening thereto and having an opening adapted to be connected to an oil lubricating system external to the filter, a removable cover for the housing, a locking means centrally assembled in the cover adapted to interlock with the upper end of the tube and assemble the housing, tube and cover into a unit, and a pressure regulated opening associated with the tube at a point on the opposite side of the filter cartridge from the opening in the tube to the primary chamber.
16. An oil filter comprising a housing, a thick body of absorptive material within the housing, the base of the absorptive material forming a diminishing conical section, the upper portion of the section being provided with rigid walls, a tube associated with the conical section, a vent in the tube within the section, the vent being positioned to feed oil in a rapidly moving stream against said rigid walls, means for feeding oil to said tube, means for removing filtered oil from the housing, and a sump in the housing positioned to receive and retain impurities washed from said rigid walls by said rapidly moving stream.
17. A cartridge for a lubricating oil filter comprising a thick mass of fibrous absorbent material pierced at its base by a hollow conical member and internally supported by a structural supporting helix, the convolutions of the helix being roughly parallel to the conical member throughout its extent.
- 40 18. A cartridge in which the sides of the cartridges are yielding, and in which the cartridge is provided with a rigid base, a mass of filtering material upon the base and with a thin flexible handle at the top anchored to the rigid base.
19. A disposable oil filter cartridge having yielding sides, a rigid base, a mass of absorbent filtering material upon the base, an oil corrodable fabric casing enclosing the absorbent material, and a thin flexible metallic handle at the top of the cartridge anchored to the metallic base.
- 20 20. A disposable unit cylindrical cartridge for an oil filter, comprising a cylindrical mass of absorbent material having an entrance face for oil near one end and an exit face near the other, said cartridge having a central opening longitudinally therethrough, the opening being materially larger at the entrance face than at the exit face of the cartridge, the cartridge about the opening at a point between the exit and entrance face being yielding and adapted to form an oil tight seal with a tube passed through said cartridge.
21. An oil filter adapted to operate on heated lubricating oil circulating in a lubricating system, comprising a housing providing space for a filtering element, a filtering element therein, by-pass means for admitting oil from the lubricating system to the housing, a tube through the housing connected to the oil inlet means by a restricted opening whereby oil pressure is substantially reduced under normal operating conditions, said tube having a restricted opening to the inlet side of the filter whereby oil pressure on the filtering element space is further substantially reduced under normal operating conditions, an outlet for removing filtered oil from the housing, said tube likewise having a communication with the outlet, and a valve at an upper portion of the tube for limiting the maximum oil pressure on the filtering element space.

JAMES E. HURN.

Patent No. 2,168,124.

August 1, 1939.

JAMES E. HURN.

It is hereby certified that error appears in the printed specification of the above numbered patent requiring correction as follows: Page 3, first column, line 75, for the word "built" read build; page 4, first column, line 49, table III; for "140°" read 120°; page 5, second column, line 65, claim 14, for "intermediately" read intermediately; and that the said Letters Patent should be read with this correction therein that the same may conform to the record of the case in the Patent Office.

Signed and sealed this 5th day of September, A. D. 1939.

Henry Van Arsdale,
